UNITED STATES PATENT OFFICE.

AUGUST SCHILLING, OF SAN FRANCISCO, CALIFORNIA.

CANISTER.

SPECIFICATION forming part of Letters Patent No. 295,434, dated March 18, 1884.

Application filed November 15, 1883. (No model.)

To all whom it may concern:

Be it known that I, AUGUST SCHILLING, a citizen of the United States, residing at San Francisco, in the county of San Francisco and 5 State of California, have invented new and useful Improvements in Canisters, of which the following is a specification.

This invention relates to a canister having a corner opening and lid both of triangular shape, the lid being hinged on one side to swing outward, and being held shut by a catch, which is arranged to engage one of its angles at a point opposite to the hinged side.

This invention is illustrated in the accompanying drawings, in which Figure 1 is a plan or top view. Fig. 2 is a cross-section in the plane $x x$ Fig. 1.

Similar letters indicate corresponding parts. The letter A designates the body of the canister, B its corner opening, and C the lid. The corner opening, B, is in the top of the canister, and both it and the lid are of substantially triangular shape, the sides of the can forming two sides of the triangle. The lid C is hinged 25 on one side, which is in this example the inner side thereof, by joints e, which are constructed to permit the lid to swing out or upward for exposing the corner opening, and when the lid is shut it is held in that position 30 by a catch, D, arranged on the canister to engage the angle of the lid which is at a point opposite to its hinged side, such angle being in this example the one which is at the proper corner of the canister; and it will be seen that 35 this catch thus acts on both of the free sides of the lid. This catch D is preferably made

in the form of a spring, in order to yield to the lid when the latter is opened or closed; and it may be made in one piece with the canister or separately therefrom, according to fancy. By 40 hinging the lid C on the inner side, in distinction from either of its outer sides, the corner opening, B, is left entirely free when the lid is opened, and a clear passage is obtained for discharging the contents of the canister; but the 45 lid can also be hinged on one of its outer sides.

What I claim as new, and desire to secure by Letters Patent, is—

1. The combination, substantially as hereinbefore described, with a canister having a corner opening of triangular shape, of a lid of similar shape to the opening, hinged on one of its sides to swing outward, and a catch arranged to engage the angle of the lid which is 55 opposite to the hinged side.

2. The combination, substantially as hereinbefore described, with a canister having a corner opening of triangular shape, of a lid similar in shape to the corner opening, hinged 60 on its inner side to swing outward, and a catch arranged to engage the angle of the lid which is opposite to the hinged side, the same being at the corner of the canister.

In testimony whereof I have hereunto set 65 my hand and seal in the presence of two subscribing witnesses.

AUGUST SCHILLING. [L. S.]
